(57) **CLAIM**

I claim the ornamental design for a lock and key, as shown and described.

DESCRIPTION

FIG. 1 is a front left perspective view of a lock and key of the new design, wherein the key is shown removed from the lock; FIG. 2 is a front right perspective view of the lock and key of FIG. 1;

FIG. 3 is a front elevational view of the lock and key of FIG. 1;

FIG. 4 is a rear elevational view of the lock and key of FIG. 1; FIG. 5 is a right side elevational view of the lock and key of FIG. 1;

FIG. 6 is a left side elevational view of the lock and key of FIG. 1;

FIG. 7 is a top plan view of the lock and key of FIG. 1; FIG. 8 is a bottom plan view of the lock and key of FIG. 1; FIG. 9 is a front left perspective view of the lock and key of FIG. 1, wherein the key is shown in a different orientation relative to the lock;

FIG. 10 is a front elevational view of the lock and key of FIG. 9;

FIG. 11 is a rear elevational view of the lock and key of FIG. 9;

FIG. 12 is a left side elevational view of the lock and key of FIG. 9;

FIG. 13 is a right side elevational view of the lock and key of FIG. 9;

FIG. 14 is a top plan view of the lock and key of FIG. 9; and, FIG. 15 is a bottom plan view of the lock and key of FIG. 9. The broken lines immediately adjacent the shaded areas represent the bounds of the claimed design while all other broken lines are directed to environment and are for illustrative purposes only; the broken lines form no part of the claimed design.

1 Claim, 12 Drawing Sheets
